CLAIM

The ornamental design for the amphibious tourniquet, as shown and described.

DESCRIPTION

FIG. 1 is a top perspective view of an amphibious tourniquet showing my new design according to an embodiment, the amphibious tourniquet being in an open configuration; FIG. 2 is a front end view of the amphibious tourniquet of FIG. 1;

FIG. 3 is a right side elevation view of the amphibious tourniquet of FIG. 1;

FIG. 4 is a left side elevation view of the amphibious tourniquet of FIG. 1;

FIG. 5 is a rear end view of the amphibious tourniquet of FIG. 1;

FIG. 6 is a top plan view of the amphibious tourniquet of FIG. 1;

FIG. 7 is a bottom plan view of the amphibious tourniquet of FIG. 1; and,

FIG. 8 is a perspective view of the amphibious tourniquet of FIG. 1 configured as a cuff for wearing on a limb or equipment according to an embodiment.

In the drawings, the fine broken lines represent unclaimed stitching, the broken lines depict a limb in FIG. 8 are for environmental purposes only, and the broken lines at the front and rear ends of the tourniquet illustrate portions of the tourniquet that form no part of the claim. None of the broken lines form a part of the claimed design.

1 Claim, 5 Drawing Sheets
